UNITED STATES PATENT OFFICE.

ALFRED G. BROWN, OF WINONA, MINNESOTA, ASSIGNOR TO UNION FIBRE COMPANY,
OF WINONA, MINNESOTA, A CORPORATION OF MINNESOTA.

REFRIGERATOR-CAR.

940,124.

Specification of Letters Patent. Patented Nov. 16, 1909.

Application filed April 12, 1909. Serial No. 489,357.

To all whom it may concern:

Be it known that I, ALFRED G. BROWN, of Winona, in the county of Winona and State of Minnesota, have invented a certain new and useful Improvement in Refrigerator-Cars; and I do hereby declare the following to be a full, clear, and exact description of the same, reference being had to the accompanying drawings, forming a part of this specification, and to the letters of reference marked thereon.

This invention relates to improvements in refrigerator cars, and more particularly to the construction of the ice bunkers or compartments, the object being to provide a bunker which may be folded back against the interior wall and ceiling of the car when the car is not traveling under ice so that the entire capacity of the car may be utilized for carrying non-perishable commodities.

Another object of the invention is to improve the circulation of the air within the car when the bunkers are filled with ice.

To these ends, the invention consists in certain novel details of construction and combinations and arrangements of parts, all as will be now described and the particular features of novelty pointed out in the appended claims.

In the drawings—Figure 1 is a longitudinal section showing one end of the car with the ice bunker constructed according to this invention, the dotted lines showing the bunker partially folded. Fig. 2 is a similar view, the bunker being shown folded. Fig. 3 is a cross-section, the front wall of the bunker being broken away. Figs. 4, 5, and 6 are detail views of the upper support for the bunker.

Similar letters of reference in the several figures indicate the same parts.

According to the present invention, the ice bunkers or holders are located at each end of the car, the end A of the car constituting the rear wall thereof.

The front wall of the bunker consists of a partition which extends transversely of the car and at a suitable distance from the end thereof, this partition being made in two sections, an upper one B and a lower one C. These sections consist of the cross-beam D—D', and the vertical beams or braces E—E', the latter being bifurcated, as shown, and to these are secured a layer of insulating material d—d, such as linofelt, preferably

waterproof, held between two layers of boards d—d'. The sections B and C are hinged together by a series of hinges D² so as to fold inwardly, as shown in Fig. 1.

To the upper end of the braces E are secured the pintle carriers E², in which the pintle E³ is fixedly held, preferably by forming the pintle and carrier angular in cross-section. To the top of the car are secured brackets F—F, arranged parallel with each other, having a straight portion f, and a depressed or rounded portion f', and the inclined portions f²—f². The ends of the pintle E³ are supported upon these brackets F—F and in the folding and unfolding of the bunker sections have a certain movement thereon which will be hereinafter described.

One end of the pintle E³ has a right angle portion e² which co-operates with an extension or lug e³ on the pintle carrier E², whereby the pintle is locked from turning when the bunker sections are in folded or unfolded position, as shown.

The bottom of the bunker consists of a series of slats or bars G, suitably spaced and secured to a bar G', said slats being hinged at the rear end to the wall of the car, as shown at H. At their forward ends, these slats G rest upon the lower bar C³ of the lower section C, certain of the slats passing between the bifurcated standards E' to which they are preferably pivotally connected, as by hinges G².

Below the bottom of the bunker is an inclined board or plate H⁴ by means of which the drip from the ice may be directed to a channel or gutter H' to be carried off. This plate H⁴ is hinged near its upper end to a block or bar H², the block being slotted or recessed as at H³ to permit the pivotal movement of the board H, as will be readily understood.

In the folding movement of the sections, the pintle ends are first elevated out of the depressed portion of the brackets F—F, so that the right angled portion e² of the pintle may clear the projection e³ on the pintle carrier. This permits the upper section B to be swung on the pintle toward the roof of the car, the pintle during this movement running out along the horizontal portion of the bracket and then back, the right angled portion of the pintle passing over the projection e³ and engaging the opposite side of

the projection e^3 , as shown in Figs. 2 and 5, when the section is fully raised thus locking it in raised position as will be readily understood. The lower section C being pivoted to the upper section, will swing with the upper section against the end of the car, the slatted bottom folding up against the car, all as shown in Fig. 2. To lock the parts in either folded or unfolded position, 10 bolts K are provided on the lower section C, these bolts being provided with teeth k , with which engages a pinion k' , the shaft of which extends through the wall of the section to be operated by a suitable key. 15 The bolts are secured within sockets k^3 — k^3 in the sides of the car.

It will be noted that a space is left between the top of the car and the top of the bunker and also that the bottom of the 20 bunker is located above the floor of the car. By such a construction a circulation of air is obtained for, as the ice melts, the air in the bunker cools, falls and passes out from below the bunker into the car. The cold 25 air passing into the car gradually becoming warm, rises and passes over the top of the wall into the bunker.

By having the bunker wall insulated the circulation is accelerated, and insures the 30 greatest effect from the cool air which cannot rise and pass back again into the ice bunker until it has traversed the entire distance between the floor and ceiling of the car. The insulation in the wall prevents 35 any cross or counter currents, and hence even when the ice is melted half way down in the bunker there must be a circulation due to the pressure of the cold air on the floor rising and forcing the warm air back 40 through the space at the top of the bunker, and into the ice chamber.

Having thus described my invention, what I claim as new, and desire to secure by Letters Patent, is—

45 1. In a refrigerator car, the combination with a bunker having a front wall formed of an upper and lower section hinged together to fold inwardly, a bottom section hinged at one end to the end wall of the car and co- 50 operating at the other end with the lower end of the lower section, said top section being suspended from the top of the car at a greater distance from the end wall of the

car than the height of said section whereby the sections may be folded inwardly and upwardly against the top and end of the car 55 respectively.

2. In a refrigerator car, the combination with a bunker having a front wall formed of an upper and lower section hinged together to fold inwardly, a bracket secured to the car roof from which the top section is freely suspended and in which said section moves back and forth during the folding movement. 60

3. In a refrigerator car, the combination with the bunker, having a front wall of two sections hinged together, a support from which the top section is suspended, and co-operating locking means on the top section 70 and support for locking said section at the extremes of its swinging movement.

4. In a refrigerator car, the combination with the ice bunker, having a sectional front wall, brackets mounted on the car roof, a 75 pintle carried by the top wall section by means of which it is suspended from the bracket, and co-operating locking means on the bracket and pintle for locking the top section at extremes of its movement, substantially as described. 80

5. In a refrigerator car, the combination with an ice bunker having hinged sectional walls, a bracket secured to the car roof having a depressed portion and a horizontal portion, a pintle carried by the top section of the bunker adapted to move back and forth in said horizontal portion of the bracket during the folding movement of the section, and to rest within the depressed portion at 90 the extremes of said movement, and means for locking the section, substantially as described. 85

6. In a refrigerator car, the combination with the sectional bunker, a bracket having a projection at one side, a pintle carried by the top bunker section working in said bracket and having an angular projection adapted to co-operate with the projection on the bracket to lock the section at the extremes of its movement. 95 100
